UNITED STATES PATENT OFFICE.

LAURA L. MILLRING, OF NEW YORK, N. Y.

DESIGN FOR A DRESSING-TABLE RECEPTACLE FOR COSMETICS OR THE LIKE.

Application filed February 3, 1927. Serial No. 20,593. Term of patent 14 years.

To all whom it may concern:

Be it known that I, LAURA L. MILLRING, a citizen of the United States, residing in the city, county, and State of New York, have invented a new, original, and ornamental Design for Dressing-Table Receptacles for Cosmetics or the like, of which the following is a specification, reference being had to the accompanying drawing, forming part thereof.

The accompanying drawing shows in Figure 1, in perspective, the dressing-table receptacle for cosmetics or the like, illustrating my new design, the cover being shown in Figure 1 as removed from the bottom portion, in order to illustrate certain features of the de-

sign more clearly. In Figure 2 is illustrated, in perspective, the dressing-table receptacle for cosmetics or the like, with the cover and bottom in assembled relation.

A feature of my design, particularly with respect to the bottom portion of the device, resides broadly in the disposition and arrangement of the smaller compartments relative to the largest compartment.

I claim:

The ornamental design for a dressing-table receptacle for cosmetics or the like, substantially as shown and described.

LAURA L. MILLRING.
